DISPENSING AND REFRIGERATING
APPARATUS

Joseph Giordano, Philadelphia, Pa.

Application March 2, 1935, Serial No. 9,192

4 Claims. (Cl. 225—21)

This invention is an improved dispensing and refrigerating apparatus.

The object of the invention is to provide an improved apparatus in which a number of different 5 beverages or other liquid materials may be stored and cooled and from which they may be selectively dispensed as required.

In the invention herein disclosed, a set of separate vessels are secured detachably to a base section and a top section cooperates with the base section to hold the vessels in assembled relation. Furthermore, the top section also forms means to promote the filling of the vessels without disassembling the apparatus and it also controls the 15 discharging of the contents of the several vessels.

The invention is disclosed on the drawing in which

Fig. 1 is a vertical sectional view through the 20 device;

Figs. 2 to 6 are sectional views taken on the lines 2—2, 3—3, 4—4, 5—5 and 6—6 of Fig. 1; and Figs. 7 to 10 show details of the invention.

The spindle 1 which extends through the center 25 of a nozzle 2 and piston or plug valve 3, is screw threaded into a rotary disk 4 and terminates in a tapered end seated in a stationary disk 5 independent containers 6 are so formed and arranged, as shown in Fig. 6, as to provide a central 30 space in which an element 7 may be positioned.

Disk 5 together with a valve body 8 forms the hollow top section of the composite receptacle and the nozzle 2 is screw threaded to said valve body. A spindle bushing 9 is adjustably screwed 35 to the lower end of nozzle 2 and a rotating means or manipulative means 11 on spindle turns the same and the disk 4 to the desired positions while a spider 12 may be employed to aid in centering the plug or piston valve 3 in the nozzle 2.

A flanged ring 13 is carried by the disk 5 and engages an outwardly extending flange on each of the vessels 6. The vessels are also secured by a second flange ring 13 to a base section 14, which has a central opening 15 through which element 40 7 may be passed in inserting said element into or removing it from the space defined by the walls of vessels 6.

The valve body 8 is secured to disk 5 by screws 45 16 and is shaped to form a space within which disk 4 is rotatably mounted. A series of symmetrically disposed nipples 17 and a nipple 18 are fitted in apertures in disk 5, said nipple 18 and said nipples 17 being located in line with the positions normally occupied, respectively, by element 7 and the vessels 6. The rotary disk 4 is

provided with an opening 19 positioned to register selectively with nipples 17, while a second opening 20 in the said disk 4 may be moved into register with opening 18, if desired.

Nozzle 2 is provided with ports 21 which may 5 be closed by the piston valve 3 when required. When said ports 21 are opened, and the disk 4 is moved to the proper position, the contents of the vessels 6 or the element 7 may be selectively discharged by way of the appropriate nipples 17, 18, 10 and apertures 19, 20, and the space in valve body 8 and through the ports 21 and nozzle 2.

A rubber ring 22 forms a packing between ring 13 and disk 5, while a gate 25 may be swingingly secured to a closure for the opening 15 in base 14 clamps 24 being provided to receive the ends of the gate when the closure is to be held in position to close said opening.

By means of a screw 23, a hand wheel provided with a collar 26 is screwed to spindle 1, 20 which passes through a rubber ring 27 in said collar. An indicator pin 28 projects from said wheel into position to cooperate with a scale on nozzle 2 to indicate the position of the openings in the disk 4 with respect to the nipples 17 25 and 18.

One or more arms 29 are secured by a member 30 to the piston valve 3 to manipulate the same. Screws 30 are passed through lugs on disk 5 and base section 14 to hold the clamping 30 rings 13 in position.

In the use of the device, any of the vessels 6 and the element 7, if said element be in the form of a hollow container, may be filled through nozzle 2, the space in valve body 8 and the respective nipple 17 or 18 after the piston valve 3 is moved to uncover ports 21 and the opening 19 or the opening 20 is brought into register with the proper nipple carried by disk 5. The contents of members 6, 7 may also be dispersed 40 selectively by inverting the device after the members 3 and 4 are properly manipulated. The element 7 may take the form of a cartridge or holder containing a suitable refrigerant or may even be the evaporator element of a refrigerator, such element projecting through the opening normally closed by gate 15. However, the element 7 may, as above described, take the form of a container, whose contents may be discharged through nipple 18, when the opening 50 19 is aligned with the latter.

I claim as my invention:—

1. An apparatus comprising a base section at one end of the apparatus and having a central opening therein; a hollow top section at the op- 55

posite end of the apparatus and a set of individual units removably arranged between said sections; said set comprising a central refrigerating unit, and a plurality of container units arranged to define a space receiving said refrigerating unit, and said top section comprising a stationary disk provided with nipples arranged in alinement with each container unit, a rotary disk provided with apertures and movable over said stationary disk to register said apertures selectively with said nipples to control communication between said vessels and said enclosed space, a nozzle having ports opening into said space, a piston valve movable to open or close said ports, an operating spindle connected to said rotary disk and projecting through and beyond the end of said nozzle and means at the end of said spindle for rotating the same.

2. An apparatus of the type defined in claim 1, in which the end of said nozzle carries graduations and the spindle rotating means carries a pointer arranged to cooperate with said graduations to indicate the position of the openings 5 in the rotary disk.

3. An apparatus of the type defined in claim 1, in which the refrigerating unit is removable through the opening in the base section and gate means provided with a latch are arranged to 10 close said opening and support said unit.

4. An apparatus of the type defined in claim 1, in which flanged retaining rings are detachably secured to the top and base sections and engage the extremities of the container units to hold the 15 same in assembled position.

JOSEPH GIORDANO.
